METAL-CUTTING SHEARS

Clarence M. Anderson, Chicago, Ill.

Application October 29, 1956, Serial No. 43,566

Term of patent 14 years

(Cl. D22—5)

FIG. 1

FIG. 2

FIG. 3

FIG. 4

Figure 1 is a side perspective view of metal-cutting shears, showing my new design.

Fig. 2 is a side elevational view thereof.

Fig. 3 is a top edge view; and

Fig. 4 is an end view looking from the left of Fig. 2.

I claim:

The ornamental design for metal-cutting shears, as shown.
